(57) **CLAIM**

The ornamental design for audio listening system, as shown and described.

DESCRIPTION

FIG. 1 is a perspective view of a first embodiment of an audio listening system in accordance with the present invention; FIG. 2 is a front view of a first embodiment of an audio listening system in accordance with the present invention; FIG. 3 is a rear view of a first embodiment of an audio listening system in accordance with the present invention;

FIG. 4 is a side perspective view of the earpiece of a first embodiment of an audio listening system in accordance with the present invention, shown separately for purposes of illustration; FIG. 5 is an opposing side perspective view of the earpiece of a first embodiment of an audio listening system in accordance with the present invention;

FIG. 6 is a top view of the earpiece of a first embodiment of an audio listening system in accordance with the present invention; FIG. 7 is a bottom view of the earpiece of a first embodiment of an audio listening system in accordance with the present invention;

FIG. 8 is a perspective view of a second embodiment of an audio listening system in accordance with the present invention; FIG. 9 is a front view of a second embodiment of an audio listening system in accordance with the present invention; FIG. 10 is a rear view of a second embodiment of an audio listening system in accordance with the present invention;

FIG. 11 is a side perspective view of the earpiece of a second embodiment of an audio listening system in accordance with the present invention, shown separately for purposes of illustration; FIG. 12 is an opposing side perspective view of the earpiece of a second embodiment of an audio listening system in accordance with the present invention; FIG. 13 is a top view of the earpiece of a second embodiment of an audio listening system in accordance with the present invention; and,

FIG. 14 is a bottom view of the earpiece of a second embodiment of an audio listening system in accordance with the present invention. The broken lines showing the environment in the Figures are for illustrative purposes only and form no part of the claimed design.

CERTIFICATE OF CORRECTION

PATENT NO. : D712,382 S
APPLICATION NO. : 29/441334
DATED : September 2, 2014
INVENTOR(S) : Brunner et al.

Page 1 of 1

It is certified that error appears in the above-identified patent and that said Letters Patent is hereby corrected as shown below:

Title Page, item (57) replace the figure descriptions with the following:

Fig. 1 is a perspective view of an audio listening system in accordance with the present invention;
Fig. 2 is a front elevational view thereof;
Fig. 3 is a rear elevational view thereof;
Fig. 4 is a side perspective view of one earpiece of the audio listening system shown separately for purposes of illustration;
Fig. 5 is an opposing side perspective view thereof;
Fig. 6 is a top view thereof; and
Fig. 7 is a bottom view thereof.

Title Page, under Description "1 Claims, 6 Drawing Sheets" should read
--1 Claims, 3 Drawing Sheets--.

In the Drawings

FIGS. 8-14 have been deleted/canceled.

Signed and Sealed this
Fifth Day of April, 2016
